UNITED STATES PATENT OFFICE.

HENNING L. SORENSEN, OF ALLENTOWN, PENNSYLVANIA.

BOAT-LAUNCHING DEVICE.

Application filed November 9, 1925. Serial No. 67,957.

This invention relates to a boat-launching device.

An object of the invention is to provide a boat launching device which, as soon as the boat is released will be in a potential condition to permit the boat to swing outboard.

A further object of the invention is to provide a simple and efficient means whereby the swinging of the boat outboard and the lowering of the boat into the water can be and preferably is controlled by one man from the boat.

A further object concerns the provision of an apparatus which is extremely simple, requiring a minimum operation on the part of a minimum number of men, and which is extremely durable and little likely to get out of repair.

A further object concerns the provision of a simple and efficient means whereby when the boat is safely in the water it can be disconnected from the lowering tackle.

The invention is illustrated in the drawings, of which

Figure 1 is a side elevation of the boat supported on its davits and showing the launching apparatus.

Figure 2 is an end elevation showing the deck of the liner in section and part of the fluid cylinder in section. This section is taken on a line 2—2 of Figure 1.

Figure 3 is a section somewhat similar to Figure 2 showing the boat swung to an outboard position, but not yet lowered, the lowered position of the boat being shown in dotted lines.

Figure 4 is a detailed section showing a means for holding the boat in position on the davit frame before it is launched.

Figure 5 is a partially enlarged section of the boat on a davit frame while it is at rest thereon.

Figure 6 is a partial elevation of one of the davit frames.

Figure 7 is a partial longitudinal section through the boat showing how the lowering tackle can be quickly released.

Figure 8 is a section on the line 8—8 of Figure 7.

Figure 9 is a partial plan view showing

the releasing pin the operation of which causes the release of the lowering tackle.

The form of the invention shown in the drawings is a preferred form, although it is understood that modifications in the construction and arrangement of the parts and in the character of the materials used may be adopted without departing from the spirit of the invention as set forth in the appended claims.

In its general aspect the invention is provided to support a boat, preferably a life-boat on the deck of a liner by means of two davit frames, one located near each end of the boat. These davit frames are so pivotally supported on the deck of a liner that as soon as the supporting plates are released these frames will tend to swing outboard. The boat is held in position on the davit frames normally by means of a plurality of suitably movable supporting plates, which, when actuated, can be moved out of the way to permit the boat automatically to swing free from the davit frames as these frames commence to tilt outboard. This tendency of the davit frames to tilt outboard is checked and braked by reason of the fact that the davit frames are provided

with suitable connections, such as steel cables to a piston in a cylinder filled with fluid, preferably oil. The flow of the oil from the cylinder and consequently the tilting of the frame is controlled by one man who may be located on the deck of the liner or preferably in the boat, which is outwardly located. This cylinder is connected to the controlling position by suitable flexible piping such as rubber hose and a valve in said pipe is adapted to be actuated by the member of the crew in charge of launching the boat. Consequently as soon as the boat is released the davits will tend to swing outwardly and the speed of this tilting can be controlled by the manipulation

of the valve. When the boat is thus swung outboard the lowering of it into the water can be likewise controlled by the manipulation of another valve in a pipe line connected to another fluid cylinder, the piston of which is connected by suitable tackle to

the boat itself. Preferably this tackle is duplex or triplex type, which will permit the travel of the boat to be several times greater than the travel of the piston.

5 Preferably the controlling mechanism is so arranged that as soon as the boat is properly launched this apparatus can be thrown overboard. It is also preferably disposed so that as the fluid, preferably oil, discharges from the cylinder, it will flow through the piping disposed on the boat and overboard adjacent the boat to calm the waters in the vicinity of the boat. As soon as the boat is safely in the water the manipulation of the single lever will cause the automatic release of the lowering tackle from the boat.

In the preferred form of my invention, which I show in the drawings, 10 represents 20 the deck of a liner. Disposed beneath the deck are two fluid cylinders 11 and 12 having pistons 13 and 14 provided with piston rods 15 and 16. These cylinders are preferably filled with oil. A pipe 17 leading to 25 the top of cylinder 12 is provided with a hand pump 18, operated by the manipulation of a lever 19 which will permit additional oil to be pumped into the cylinder 12 through pipe 20 leading to a suitable source 30 of oil.

The piston 13 is connected by preferably 35 flexible steel cables, one of which, 21, is shown, passing over pulleys 22 and 23 and connected to the rear end 24 of a davit frame 25. There are two davit frames of 40 this type for each boat, one located near each end of the boat. These davit frames have a vertically extending arm 26 and a forwardly extending portion 27, the boat 28 being supported or resting on the latter. The boat is held on the davit frames between two supporting plates 29 and 30, there being a pair of these plates at each end of the boat. The plates 30 are movable, being 45 pivotally connected as at 31, (see Figure 5) to a movable post 32, having a normal position as shown in full line in Figure 2. This post is connected to a rod 33 adapted to be actuated by the manipulation of a hand wheel 34 through suitable thread and sleeve connections designated by the numeral 35 in Figure 5. When this hand wheel is manipulated it will draw the posts 32 to the dotted position shown in Figure 5, which will lower the movable plate 30 to the dotted position shown in Figure 5, thus removing it from the path of the keel 36 of the boat 28, so that the boat will be free to swing off the supporting portion 27 of the davits as hereinafter to be described.

The shaft 31 extends across beneath the boat to the other davit frame and another post similar to 32 is located at the other end of the shaft and this post is connected to another movable plate 30, which is likewise

50 moved by the manipulation of the hand wheel.

Each of the davit frames are pivotally supported on a shaft 37 mounted on suitable bearing brackets 38 and 39 (see Figure 1). Pulleys 40 are disposed at each end of the shaft 37 to receive flexible connections such as steel cables 41 hereinafter to be described.

The pipe 42 extends from the cylinder 11 to the boat 28 where a valve 43 is located in said pipe. The valve 43 as shown is loosely supported on the standard 43^a projecting from the top of the boat, so that it is disengaged therefrom when the boat is swung from its davits. It is immaterial, however, how it is supported, or on which part of the boat, so long as it is free to leave the boat when being lowered. As shown in Figure 4 a latch finger 44 connected to the davit arm 26 engages the side of the boat 28 to hold 85 it on the davit more securely. This finger may be lifted to disengage it from the boat when the boat is to be launched.

When it is necessary to launch the boat the passengers get into the boat and this increased weight being supported on the plates 27 of the davit frame will tend to tilt the davit frames around the shaft 37. This will put a strain on the cables 21 and the piston 13, which will compress the fluid in the cylinder. By opening the valve 43 a man in the boat will permit the fluid to flow out at whatever speed he desires, thus permitting the davit frame to tilt. Before he opens the valve, however, he releases the finger 44 and manipulates the hand wheel 34 to move the plates 30 out of the way of the keel of the boat. As the oil flows out of the cylinder 11 the davit tilts to the position shown in Figure 3. The oil flowing from the cylinder 11 may be allowed to flow overboard or 95 may be permitted to flow through suitable piping to any suitable source or container not shown.

When the boat is in the position shown in Figure 3 in full lines, it is necessary to lower it into the water. This is done by opening a valve 45 (see Figure 7). This valve is connected on one side to a flexible piping 46 leading to pipe 17 previously mentioned, this pipe extending to the top of cylinder 12. The previous manipulation of the hand pump 18 has forced an extra quantity of oil into the top of this cylinder 12, thus depressing the piston 14 further down and by reason of the connection of the block 47 and the cables 41 to the boat initially lift the body of the boat from the davit frames. When the valve 45 is open, however, the fluid will be forced out by reason of the weight of the boat through the valve 45 into hose or pipes 48 and 49 which are preferably draped over the ends of the boat in coils such as 50 and 51 (see Figure 1) from which the oil will be discharged overboard 130

at the ends of the boat tending to calm the waves.

The fact that the cable 41 is a triplex cable between the sheave 47 and the multiple pulley 68 (see Figure 3) permits the boat to drop three times as far as the piston 14 moves. After the boat is in the water the valve 45 can be thrown overboard. It is also obvious that instead of allowing oil to discharge on the water it can be permitted to discharge into suitable containers on the vessel, whence it can be pumped back into the cylinder if desired, and this pumping action can be utilized to raise the boat from the water and to restore the davit frame to its original position. Furthermore, it is obvious that the control of the tilting of the davit frame and the lowering of the boat can be effected from the deck of the steamer if desired, instead of the boat being launched, although the latter method of control is preferable, since one man in the boat itself can very nicely regulate its movements.

After the boat is in the water a handle 51^a (see Figure 1) is operated to pull on two links 52 and 53 moving them in opposite directions as shown in Figure 9. One of these links is shown as running over a pulley 54 and connecting to a pin 55, which by reason of the movement of the handle 51^a will be withdrawn from a hole in a bar 56 connected to the end of a rod 57 (see Figure 7) on the end of which a weight 58 is supported. This rod is pivoted at 59 and is connected to a hook 60. This hook engages a link 61 which is connected to the lower end of one of the cables 41 supporting the boat. The shaft 59 and the hook 60 are mounted on bracket frames 62 fastened in the bottom of the boat and located within suitable wall casings such as 63 at each end of the boat. It is understood, of course, that there are two cables 41, one at each end of the boat and lying over two davit frames, these cables being connected to the same sheave 47 by engaging, as shown in Figure 1, with pulleys 64 at the top of each davit frame, a pulley 65 intermediate the length of the davit frame and then running over the pulleys 40 in connection with each davit frame. The cables then proceed beneath the deck 10 and pass over pulleys 66 and 67 after which they pass over a multiple pulley 68 mounted beneath the deck and then are connected to the sheave 47.

It is quite apparent from consideration of this description that the device is as simple as any mechanism of this sort can be, that it is capable of a very high degree of control and can be operated with as much speed as can be desired under the usual conditions of launching a boat. One of the important points in regard to the invention is that the entire apparatus is controlled by one man and that the speed of the action is

regulated by him, and is entirely in response to gravity, minus the checking action of the fluid brakes. It is believed that this is the first time that a tilting davit of this kind has ever been disclosed, which, merely by reason of the weight of the passengers in the boat supported on the davit will tend to move the boat to an outboard position.

What I claim is:

1. A boat launching device which comprises a pivoted davit supporting a boat and adapted to tilt due to the weight of the boat, fluid controlled means connected to the davit for controlling the speed of tilting, and means loosely supported in the boat under the control of an operator for controlling said fluid means.

2. A boat launching device which comprises a davit frame pivoted to the deck of a vessel, a boat supported thereon, said davit adapted to tilt due to the weight of the boat, fluid controlled means for regulating the speed of tilting of the davit, and a second fluid controlled means for regulating the speed of lowering the boat from the davit into the water, means in the boat under the control of the operator to control the first mentioned fluid controlled means, and means loosely supported in the boat under the control of the operator for controlling the second mentioned fluid controlled means.

3. A boat launching device which comprises a davit frame pivoted to the deck of a vessel, a boat supported thereon, said davit adapted to tilt due to the weight of the boat, a fluid cylinder having a piston, connections between the piston and the davit frame, and means loosely supported in the boat under the control of an operator to regulate the discharge of fluid from the cylinder whereby the speed of tilting of the davit frame can be controlled.

4. A boat launching device which comprises a davit frame pivoted to the deck of a vessel, a boat supported thereon, said davit adapted to tilt due to the weight of the boat, a fluid cylinder having a piston, connections between the piston and the davit frame, and means loosely supported in the boat under the control of an operator to regulate the discharge of fluid from the cylinder whereby the speed of tilting of the davit frame can be controlled, and a second fluid cylinder having a piston, connections between said piston and the boat, and means under the control of the operator to regulate the discharge of the fluid from said second cylinder whereby the speed of the descent of the boat from the davit frame can be regulated.

5. A boat launching device which comprises a davit frame, a boat supported thereon, a fluid cylinder having a piston, connections between the piston and the boat and

means loosely supported in the boat under the control of an operator for regulating the discharge of fluid from its cylinder, whereby the speed of descent of the boat from the davit can be controlled.

6. A boat launching device which comprises a davit frame, a boat normally resting thereon, a fluid cylinder having a piston,

means connecting the piston to the boat and means whereby additional fluid can be pumped into the cylinder to move the piston a sufficient amount whereby the boat will be slightly raised from the davit prior to being launched.

HENNING L. SORENSEN.
